Primary Examiner — Nathan M Johnston*(74) Attorney, Agent, or Firm* — Panitch Schwarze Belisario & Nadel LLP(57) **CLAIM**

The ornamental design for a medication mixing apparatus, as shown and described.

DESCRIPTION

FIG. 1 is a front perspective view of a medication mixing apparatus in accordance with our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The features shown in broken lines show portions of the design that form no part of the claimed design.
